DESIGN FOR A FLUORESCENT LIGHTING FIXTURE

John C. Sabatini, West Englewood, N. J., assignor
to Colonial Neon Company, Inc., North Bergen,
N. J., a corporation of New Jersey

Application March 27, 1945, Serial No. 118,728

Term of patent 14 years

(Cl. D48—23)

To all whom it may concern:

Be it known that I, John C. Sabatini, a citizen
of the United States and resident of West Engle-
wood, county of Bergen and State of New Jersey,
have invented a new, original, and ornamental
Design for a Fluorescent Lighting Fixture, of
which the following is a specification, reference
being had to the accompanying drawing, forming
part thereof.

Figure 1 is a perspective view of a fluorescent
lighting fixture showing my new design.

Figure 2 is a fragmentary view disclosing one
end from a position below the fixture.

I claim:

The ornamental design for a fluorescent light-
ing fixture, as shown.

JOHN C. SABATINI.
